AUTOMATIC VOLUME CONTROL CIRCUIT

Alfons Andreatta, Berlin, Germany, assignor to
 Allgemeine Elektricität Gesellschaft, Berlin,
 Germany

Application November 30, 1935, Serial No. 52,323
 In Germany February 20, 1935

1 Claim. (Cl. 250—20)

Automatic volume control in radio apparatus is obtained, in general, in that the grid bias of amplifier, or detector, tubes is varied in relation to the high frequency potential applied to the input of the receiver. The tubes in this case are so constructed that various grid biasing potentials correspond to different degrees of amplification. In the drawing, the usual circuit is represented in Fig. 1. Figs. 2 and 3 show the two different modifications of the invention.

The control potential at resistor 2 and produced by tube 1 is applied, across resistors 3 and 4 to the first control grid 6 and across resistor 7 to the second control grid 8 of tube 5. In the circuit shown, grid 3 is not supplied by the entire control potential, but receives only a part thereof for instance one half of the control potential. A resistor 9 through which a voltage drop is produced by the cathode current, supplies a further grid bias for the tube 5. The tube 5 has three biasing potentials applied:

(1) A negative bias derived from the resistor 9 and whose value depends upon the cathode current.

(2) The control potential at resistor 2 which is likewise negative.

(3) A positive bias at resistor 10 which technically cannot be suppressed and which is in opposition to the potentials 1 and 2.

Ordinarily, the resistors are so dimensioned that at a control potential equal to zero, both grids of the tube to be controlled have a low negative bias of, for instance, one volt impressed thereon in order to prevent grid current. This is accomplished by increasing the voltage drop at resistor 9 by, for instance, one volt above that at resistor 10. If a high-frequency potential is applied to the input resistor 4 which is amplified in the tube 5 and detected in the diode path 11, the grid potentials of tube 5 become negative in view of the control potential appearing at the resistor 2.

Consequently, the plate current of tube 5 will be decreased. As a result thereof there occurs a further change of the grid voltage of tube 5, namely due to the fact that as a result of the decrease in the plate current, the voltage drop through the resistor 9 becomes smaller. As will be seen from the following data, this voltage variation is undesirable, since it acts against the control potential and decreases the range of action of the control.

It will be assumed that the available variation of the high-frequency potential at resistor 4 produces at resistor 2 a control potential of, for in-

stance, 0 to 6 volts. As already pointed out above only one half of the control potential is used for the control of grid 8. If the bias of tube 5 at zero control potential is equal to -1 volt, there thus appears at grid 8 a variation of -1 to -4 5 volts, and at grid 6 a variation of -1 to -7 volts.

In order to obtain a wide range of control it is desirable to utilize fully these voltages for the control. However, this cannot be done in the circuit shown, since the voltage drop at resistor 10 9 is in opposition to the control potential. It is necessary to provide a bias of, for instance, -3 volts at the biasing resistor 10 of tube 5 in view of the considerable tone frequency potential at the grid of the tube. 15

At the control potential -6 volts, grid 6 has a potential of -6 (resistor 2) +3 (resistor 10) -1 (resistor 9) = -4 volts, grid 8 has the potential -3 (from resistor 2) +3 (resistor 10) -1 (resistor 9) = -1 volt. In place of a control of -1 to -7, 20 or -1 to -3 volts there occurs a control in the range from -4 to -1 or 0 volt, i. e. the control fails at the second grid. It, therefore, follows that despite the considerable number of elements and despite the control of two grids, an entirely 25 unsatisfactory control will be obtained with the known circuit, and which is far from sufficient for compensating most of the fading phenomena.

The aforementioned drawback is overcome by the automatic volume control circuit described 30 in the following. With this circuit it is possible to attain the widest possible control determined by the exponential characteristic of the tube or tubes used, and by the control potential produced at resistor 2. In the new circuit the direct current flowing through resistor 9 is maintained constant so that also a constant voltage drop through the resistor will be produced. The direct current potential appearing at resistor 10 is constant as 35 aforementioned. The negative grid bias results from the difference of the direct current potentials produced at resistor 9 and at resistor 10, in addition to the control potential at resistor 2. Since in view of the arrangement of the circuit, the potentials at the resistors 9 and 10 are constant, the variation of the negative grid biasing potential depends only upon the potential at resistor 2, so that a maximum control will be attained. In the example of the calculation above 40 given, there would in fact be obtained for grid 6 a control potential of -1 to -7 volts (as compared with -1 to -4 volts of the hitherto known arrangement), and for grid 8 a control potential 45 of -1 to -4 volts (in the hitherto known ar- 50 55

angement no control at all was obtained through grid 8).

The circuit diagrams 2 and 3 show examples for the practical application of the invention. In the 5 circuit of Fig. 2, the emission current of the end tube is at the same time passed as additional direct current through the resistor 9 whereby practically a constant voltage drop through resistor 9 is obtained since the emission current of the end 10 tube is larger by one order than the emission current of tube 5.

The plate current of end tubes as used at this 15 time in radio apparatus with volume control is approximately 40 mA, and the plate current of a controlled tube is 3 to 4 mA. While in the above example the voltage at resistor 9 fluctuates on account of the cathode current within the limits between 0 and 3 volts, the voltage produced by the cathode current remains practically constant 20 when applying the invention. Those skilled in the art will realize that resistor 9 should have its resistance reduced to a value such that the total current flow therethrough will provide the desired normal operating bias for the grid 6.

25 A further example of applying the invention is shown in Fig. 3. In this circuit a practically constant voltage drop is produced through the resistor 9 by the additional current of the voltage divider of the screen grid. This is accomplished 30 in that the screen grid potentiometer consisting of the resistors 12 and 13 is not grounded at the pole as is usually done, but is placed at the cathode of the tube 5 so that the potentiometer lies in series to the resistor 9. The extent to which the 35 basic voltages existing at resistor 9 shall be independent of the cathode current of tube 5 simply depends upon a corresponding dimensioning of the resistors 12 and 13.

The automatic volume control according to the

invention, may also be obtained in another way, for instance, the exciting current of the field coil of a dynamic loudspeaker may be passed through the resistor 9. This has for its effect an especially great independence from the cathode current 5 of tube 5 since the latter is only $\frac{1}{20}$ of the exciting current.

What is claimed is:

In a radio receiver comprising at least one signal transmission tube provided with at least a 10 signal input electrode, a cathode and an output electrode, an impedance in the space current path of the tube developing a first direct current voltage, a signal rectifier including an impedance 15 in its space current path for developing a second direct current voltage which varies in magnitude with the signal amplitude, a source of direct current voltage of relatively fixed magnitude, said signal input electrode being connected to said cathode through an automatic gain control path 20 including at least a portion of said rectifier impedance, said fixed source and at least a portion of said first impedance arranged in series relation, the voltage of said fixed source being in polarity opposition to the first and second direct current 25 voltages and the latter two voltages biasing said signal input electrode negatively, and means for maintaining said first voltage substantially independent of the changes in negative bias of said signal input electrode, said means comprising a 30 direct current source connected to said first impedance in such a manner that the current thereof flows through the impedance, the magnitude of the last source being sufficiently greater than that of the transmission tube space current that the 35 said first direct current voltage remains substantially constant in value.
